UNITED STATES PATENT OFFICE.

WALTER J. DREW, OF GRAND RAPIDS, MICHIGAN, ASSIGNOR TO THE
BISSELL CARPET SWEEPER COMPANY, OF SAME PLACE.

DESIGN FOR A CARPET-SWEEPER CASING.

SPECIFICATION forming part of Design No. 18,380, dated June 12, 1888.

Application filed February 23, 1888. Serial No. 265,053. Term of patent 14 years.

To all whom it may concern:

Be it known that I, WALTER J. DREW, a citizen of the United States, residing at Grand Rapids, in the county of Kent and State of Michigan, have invented and produced a new and original Design for Carpet-Sweeper Casings, of which the following is a specification.

My invention relates to carpet-sweepers; and it consists in a new and original design for the sweeper-casing, as hereinafter fully set forth, and definitely pointed out in the claim following this specification.

In the accompanying drawing the figure is a perspective view illustrating the design.

Referring to the said drawing, the reference-numeral 1 denotes the sweeper-casing, the mechanical adjuncts thereof not being shown.

The casing is of rectangular form, the two longer angles upon each side being beveled off by an inclined panel, 2. The flat top of the

casing consists of a central panel, 3, and two parallel panels, 4, upon each side thereof, said panels 4 being raised or in relief, the height of the relief being equal, or substantially equal, to the thickness of the panels. The panels 4 may overlap the central panel, 3. I have shown their outer edges as projecting over and beyond the edges of the inclined panels. 25

What I claim is—

The design for a carpet-sweeper case, consisting of a box having side panels, 2, a central top panel, 3, and two adjacent panels, 4, raised above the central panel at the sides thereof, substantially as shown and described.

In testimony whereof I affix my signature in presence of two witnesses.

WALTER J. DREW.
